Primary Examiner—James Gandy*Assistant Examiner*—Linda Brooks*Attorney, Agent, or Firm*—Amster, Rothstein & Ebenstein[57] **CLAIM**

The ornamental design for an outdoor beverage display stand, as shown and described.

DESCRIPTION

FIG. 1 is an isometric view from the front, top and one side of an outdoor beverage display stand showing my new design;

FIG. 2 is an isometric view thereof from the back, top and the one side;

FIG. 3 is a top plan view thereof;

FIG. 4 is a bottom plan view thereof;

FIG. 5 is a side elevation view thereof from the one side, the other side being a mirror image thereof;

FIG. 6 is a view similar to FIG. 1, but showing the display in a position of use, with the doors open and the roof pivoted upwardly; and,

FIG. 7 is a view similar to FIG. 6, but showing the display with the upstanding front bottom panel shown in FIG. 6 removed to reveal details of internal construction.

The feet, surface indicia, and environmental structure shown in broken lines in FIGS. 1,2,3,4,5,6, and 7 are for illustrative purposes only and form no part of the claimed design.
